COMBINED PANEL AND DRAWER PULL FOR A FOOD WARMER OR THE LIKE

John R. Gomersall, Elgin, Ill., assignor to McGraw-
Edison Company, a corporation of Delaware

Application January 20, 1955, Serial No. 34,091

Term of patent 14 years

(Cl. D10—8)

Figure 1 is a perspective view showing a combined panel and drawer pull for a food warmer or the like embodying my new design;

Fig. 2 is a plan view thereof; and

Fig. 3 is a side view thereof.

The dominant features of my design reside in the portions shown in solid lines.

I claim:

The ornamental design for a combined panel and drawer pull for a food warmer or the like, substantially as shown and described.
